FRANÇOIS XAVIER JOSEPH ALBERT DELAS, OF PARIS, FRANCE

HEAT EXCHANGER

Application filed May 17, 1932, Serial No. 611,906, and in France September 28, 1931.

The present invention relates to apparatus in which an exchange of heat is made between two fluids, through partitions separating said fluids, such as surface evaporators or the like; it relates more particularly to the kind of such apparatuses wherein one of the fluids circulates inside a set of pipes the outside of which is bathed by the other fluid. In such devices, it happens often, owing to the nature 10 of the other fluid, that said fluid deposits scale on the pipes; in such case the exchange of heat is much lessened and it becomes necessary from time to time to remove said scale. This may necessitate stopping the apparatus 15 for a long time, when the hardness of the scale renders its removal difficult.

It has been already proposed to clean the pipes from said scale during the working and just when they are formed, by slipping on the 20 pipes tubular members of greater diameter which, consequently, lean on the pipes by a generatrix, said members being rotated, say by the movements of the fluid inside which they bathe. Such a device presents several 25 drawbacks; it is necessary to take in pieces the apparatus if a tubular member is to be removed and another one substituted therefor; on the other hand the tubular members having substantially the same length as the pipes do 30 not bear regularly thereon, the pipes have of course a sag the value of which depends on their size and nature, the tubular member presents also a sag having another value; thus, the tubular member touches the pipe 35 only at separated points and between these latter a layer of scale could remain on the pipe without being torn away therefrom since the tubular member did not rub thereupon.

The invention has for its object a device 40 avoiding said drawbacks, supported by a shaft in such a way that it may be easily rotated; on each pipe are slipped a number of tubular members of small length, say 10 to 15 cm. in order that they practically touch the pipes along their whole length, said members are counterweighed in order to cause 45 them to keep always the same angular position during the rotation of the set of pipes, and thus to rub on the surface of said pipes 50 instead of rolling thereon; and to allow said

members to be easily put in place or removed, they are slotted along a generatrix, the slot being smaller than the outer diameter of the corresponding pipe, and the member being resilient enough to allow said slot to be temporarily expanded when the tubular member is put in place or removed. 55

The following is, by way of example, a disclosure of an apparatus according to the invention, with reference to the accompanying drawing in which: 60

Fig. 1 is a diagrammatical cross-sectional view of an apparatus according to the invention;

Fig. 2 shows a part of a pipe with the tubular members thereon; 65

Fig. 3 is a cross-section of the same;

Fig. 4 shows in cross-section a modification of the tubular member.

Fig. 1 shows a device according to the invention which may be used by instance for evaporation of sea water in order to obtain fresh water by distillation, but is not restricted to said use. 70

The apparatus comprises a casing 1 provided with an inlet aperture 2 by which the sea water arrives inside, and with an outlet aperture or exhaust 3 by which the steam produced flows out towards a condenser. 75

On two opposite walls of casing 1 are disposed fluid tight bearings 4 and 5 through which pass tubular semi-shafts 6 and 7; said tubular shafts are ended in fluid-tight joints 8, 9 by which they are connected to inlet and outlet pipes 10 and 11 by which the heating fluid arrives and flows out. Shafts 6 and 7 are connected to and communicate with two hollow boxes, 12, 13 connected the one with the other by a set of pipes 14. On shaft 5 is keyed a pulley 21 allowing by means of a motor (not shown) to rotate shafts 5, 6, boxes 12, 13 and set of pipes 14. The heating fluid, by instance high pressure steam, heats the sea water across the walls of pipes 14, and as said above the steam thus produced flows away by exhaust 3 towards a condenser; while evaporating, the sea water deposits the dissolved salts, and as it is well known this sediment has a tendency to deposit especially 85 on the warm walls of pipes 14, and to form 90

25 95
30 100

scale thereon thus preventing the transmission of the heat from the inside to the outside of said pipes. In order to tear out said scale and according to the invention a number of 5 tubular members 15 are loosely slipped on each pipe 14, each member 15 having a length substantially equal to 10 to 15 centimeters.

- Figures 2 and 3 illustrate the manner in which members 15 are made and put in place.
- 10 Said members present a generally tubular shape but the thickness of said tube is not uniform and is much greater in 16 than elsewhere. Owing to such dissymmetry the portion 16 of the tube being the heaviest one re- 15 mains always in the lower part during the rotation of the set of pipes 14, part 16 plays thus the part of a counterweight, it is then obvious that member 15 shall consequently rub on the upper generatrix of pipe 14 and 20 since, during the rotation, each generatrix of pipe 14 and since, during the rotation, each generatrix of pipe 14 is at its turn the upper one, the whole outer surface of pipe 14 shall be rubbed by tubular member 15, said friction 25 tearing out the sediment just as it is formed.

Owing to the slight length of members 15 their sag is practically zero and thus the members touch the corresponding pipes along 30 their whole length. As said members are allowed to take a slight longitudinal displacement, the gaps between them do not remain always just in the same places and so the whole surface of the pipes is swept by said members 15.

35 As stated above tubular members 15 are longitudinally slotted, said slot 17 having a width a little smaller than the outer diameter of pipes 14 in order to maintain member 14 thereon, as tubular members 15, especially in 40 these thinnest parts, have sufficient resiliency, when it becomes necessary to put in place or to remove them, it is easily done by exerting a strain on both edges of the slot for widening this latter enough to allow the pipe to pass 45 therethrough. It is thus easy as well to remove a worn off tubular member as to put in place a new one.

The scale worn off by the action of members 15 falls to the bottom of the casing and 50 is exhausted therefrom say by an aperture 22.

Fig. 4 shows a modification of the tubular member constituted by a slightly curved strip 18 leaning on the pipe and a heavy stem 19 55 playing the part of counterweight; strip 18 and stem 19 being connected by resilient rings 20 partly broken to form slot 17.

Of course it is advantageous to make the rubbing members 15 or 18 of a material softer 60 than that of the tubes in order to avoid the wearing off of these latter.

What I claim is:

1. An apparatus for exchange of heat between two fluids comprising a set of pipes, 65 means for causing one fluid to circulate in-

side said pipes, means for causing the other fluid to bathe the outside thereof, means for rotating said set of pipes around an axis, around each pipe a tubular member loosely slipped thereon, on each of said members a counterweight heavy enough for maintaining it in the same angular position during the rotation of the set, each of said members being provided along a generatrix with a slot the width of which is smaller than the outside diameter of the corresponding pipe, said members being resilient enough to allow said slot to be enlarged so that the width thereof becomes larger than the diameter of the corresponding pipe.

2. An apparatus for exchange of heat according to claim 1 wherein a number of slotted and counterweighed tubular members, each having a length of substantially 10 to 15 centimeters, are loosely slipped on each pipe.

3. In an apparatus for exchange of heat between two fluids according to claim 1 tubular slotted and counterweighed members each consisting in a slightly curved strip, a heavy stem, resilient broken rings connecting said strip and said stem.

4. An apparatus for exchange of heat between two fluids according to claim 1 comprising a casing, means for causing one fluid to circulate therein, two opposite bearings provided in the walls of said casing, two tubular semi-shafts journaled in said bearings, two hollow boxes fastened on the ends of said semi-shafts, pipes parallel to the axis of said shaft connecting the two boxes, means for causing the other fluid to flow through said shafts, boxes and pipes, on each pipe slotted and counterweighed tubular members in the bottom of the casing, an exhaust for the scale taken off the outside of the pipes by the friction of the tubular members.

In testimony whereof I have affixed my signature.

FRANÇOIS XAVIER JOSEPH ALBERT DELAS.
